JIG

Charles E. Galley, Chicago, Ill., assignor to
Luxene Inc., a corporation of Delaware

Application March 31, 1943, Serial No. 481,251

2 Claims. (Cl. 29—256)

This invention comprises a jig for disassembling members constituting an extrusion device or gun designed for forcing material into a denture mold.

The jig and the parts of the device necessary for understanding the invention are illustrated in the accompanying drawing in which

Fig. 1 is a plan view of the jig;

Fig. 2 is an end view thereof;

Fig. 3 is a side view thereof; and

Fig. 4 is a cross section on the line 4—4 of Fig. 1.

The extrusion device or gun, for which the jig is intended, is made of a barrel *a* which is internally threaded for engaging a screw-threaded end *c* of a nozzle *b*; these are shown assembled in dotted lines on Fig. 1, and the nozzle *b* is shown apart from the barrel *a* in full lines on the same figure. The nozzle *b* has the other end *e* threaded for engaging a sprue opening in the lid of a mold flask, and it has an intermediate hexagonally shaped body portion *f* for engagement by a wrench. Within the nozzle *b* there is a slideable piston *d*. When the gun is in use the nozzle *b* is attached to the flask lid by screwing the threaded end *e* into the sprue opening (using a wrench on the portion *f* for this purpose), placing a charge of denture material in the nozzle, inserting the piston *d*, and then attaching the barrel *a* which carries a spring-pressed part contacting the piston; as the barrel *a* is turned on the nozzle *b*, the piston *d* is caused to travel within the nozzle and thus forces the material into the flask. When the molding operation is completed, it then becomes necessary to take the gun apart for cleaning and a new charge; but this is not easily accomplished, because the material extruded from the gun is one that sets up and hardens during the molding process, and it tends to jam the piston within the nozzle. The tool or jig forming the subject matter of this invention has for its object the ready disassembling of the extrusion device or gun without injuring the parts.

The jig comprises a bed plate 10 provided with holes 11 for bolting it to a bench. On an extension 12 of the plate there projects upwardly a boss 13; the boss has a parallel walled slot 14 which divides it into two sections 15 and 16. The section 15 has a hexagonally or other polygonally shaped depression 17 corresponding to the body portion *f* of the nozzle *b*, and the section 16 has a circular depression 18 for accommodating the end *e* of the nozzle; the slot provides a face 19 against which the body portion *f* is placed. By

merely dropping the portion *f* of the nozzle into the depression 17, the barrel *a* can be readily unscrewed from the nozzle *b* by applying a wrench to the barrel.

5 On the bed plate 10 there also extends a series of upward projections which are in axial alignment. One of these is an internally threaded sleeve 20 in which there is mounted a long jack screw 21 with an operating handle 22. The next 10 projection is a rest or support 23 having a depression 24 for receiving the threaded end *c* of the nozzle *b*. The third is a boss 25 constructed like the boss 13 and having a slot 26 with a slot face 31, a hexagonal depression 27 in a section 28, and a rounded depression 29 in a section 30 for mounting and restraining the nozzle *b* against 15 turning and forward movement; the body portion *f* of the nozzle *b* fits into the depression 27 and engages the face 31, the threaded end *e* lies in the depression 29, and the other threaded end *c* is supported in the depression 24 with the axis of the nozzle in line with the screw 21. As the screw 21 is turned into contact with the piston *d* within the nozzle, movement of the nozzle is 20 prevented by its engagement with the slot face 31. By this means there is a gradually increasing force exerted upon the piston *d* until the piston starts to move, and at a rate such that any tendency to tearing the walls of the nozzle is 25 eliminated.

The jig as a whole constitutes an assembly of 30 cooperating parts for the separation of the nozzle from the barrel and the ejection of the piston from the nozzle of the gun. It has been found 35 to be a necessary adjunct to the utilization of the gun for extrusion of denture material into a denture molding flask as there is a tendency for freezing of the piston in the nozzle, and attempts to drive it out by ordinarily available means have 40 caused tearing and consequent destruction of the nozzle.

What is claimed is:

1. Jig for disassembling a device including a 45 nozzle with a body portion of polygonal cross section with threaded ends extending from the body portion and a piston slideable therein, comprising in combination a bed plate, a boss projecting from the bed plate and slotted to form two sections, one of said sections having a depression of polygonal shape for receiving the body portion of the nozzle and the other section having a depression of semi-circular form for a threaded end of the nozzle, a rest for the opposite threaded end of the nozzle, and a screw in threaded engagement with 50 a sleeve supported on the bed plate, said rest and 55 a screw in threaded engagement with

sleeve being in axial alignment with the boss for directing the screw into contact with the piston within the nozzle and for forcing the piston therefrom axially of the nozzle.

2. A jig for disassembling a device that includes a nozzle with a body portion of polygonal cross-section with threaded circular ends extending from and of a diameter less than that of the body portion and a piston slidable in the nozzle comprising in combination a piston-forcing means and means for supporting the nozzle in axial alignment with the piston-forcing means and

against rotary and axial displacement, said nozzle-supporting means comprising a boss slotted transversely to form two sections, one of said sections having a depression of polygonal shape for engaging the body portion against rotary displacement and the other portion having a depression of semi-circular form to fit and receive a threaded end extension and to form an abutment engaging the body portion against longitudinal axial movement.

CHARLES E. GALLEY.
